UNITED STATES PATENT OFFICE.

WILLIAM L. SOMMER, OF NEW YORK, N. Y.

DESIGN FOR A BAGATELLE-BOARD.

SPECIFICATION forming part of Design No. 26,187, dated October 13, 1896.

Application filed September 1, 1896. Serial No. 604,587. Term of patent 7 years.

To all whom it may concern:

Be it known that I, WILLIAM L. SOMMER, a citizen of the United States, and a resident of the city of New York, in the county of New York and State of New York, have invented a new and original Design for Bagatelle-Boards, of which the following is a specification.

In the accompanying drawing, forming a part of this specification, a face view of a bagatelle-board embodying my new and original design is shown.

The leading features of my design are the wreath, the eagle, and the shields.

The board A has the usual runway, pins, and poekets and in addition thereto the

wreath B, the eagle C, and the shields D, along some of the edges of which pins are arranged.

Having described my invention, what I claim as new, and desire to secure by Letters Patent, is—

The design for bagatelle-boards, substantially as herein shown and described.

In testimony that I claim the foregoing as my invention I have signed my name, in presence of two witnesses, this 28th day of August, 1896.

WILLIAM L. SOMMER.

Witnesses:

OSCAR F. GUNZ,
